JAMES HENRY LITTLER, OF MANLIUS, NEW YORK, ASSIGNOR TO S. CHENEY & SON, OF MANLIUS, NEW YORK, A CORPORATION OF NEW YORK.

ROTARY GRINDER.

Application filed January 29, 1925. Serial No. 5,603.

This invention relates to a grinding machine preferably of the hand operated type adapted to be clamped upon a bench or other suitable support for grinding various kinds 5 of articles such as the poppet valves for internal combustion engines, drill points, shears, chisels and analogous objects and also involving the use of a trueing device by which one of the end faces of the grinder 10 may be kept in a perfectly flat plane at right angles to the axis of rotation.

The main object is to provide the machine with suitable guide holders for the various kinds of work to be operated upon and also 15 to enable the trueing device to be operated at will for trueing one of the end faces of the grinder when desired, all of said work holders and trueing device being installed on the machine as a unitary part thereof and 20 each having a particular relation to the grinder.

One of the specific objects is to enable the valve holder to be adjusted to different angles to conform to the angle of the seating face of the valve with the axis of the 25 valve stem.

Another object is to provide the chuck for receiving and holding the valve stem with double conical ends cooperating with opposite 30 end thrust bearings whereby the longitudinally operated chuck may be compressed upon the valve stem throughout the major portion of its length and thereby reduce the liability of vibration of the valve during the 35 refacing process.

Another specific object is to provide the drill holder with means for centering, holding and adjusting the drill at the proper angle to the grinder for producing the desired angular cutting face.

Other objects and uses relating to specific parts of the machine will be brought out in the following description.

In the drawings:—

45 Figure 1 is a perspective view of a grinding machine embodying the various features of this invention.

Figure 2 is an enlarged horizontal sectional view taken on line 2—2 Figure 1.

50 Figure 3 is an enlarged vertical sectional view taken on line 3—3 Figure 1.

Figure 4 is a horizontal detail sectional view taken in the plane of line 4—4 Figure 3.

55 Figure 5 is a detail vertical sectional view taken in the plane of line 5—5 Figure 2.

Figure 6 is an enlarged vertical sectional view taken on line 6—6 Figure 1.

Figure 7 is a detail sectional view taken in the plane of line 7—7 Figure 2.

As illustrated, this invention comprises an 60 upright main supporting frame —1— having vertically spaced clamping arms —2— and —3— for receiving between them a portion of a bench or table top upon which the machine is adapted to be mounted, the arms 65 —2— being arranged in horizontally spaced relation for engagement with the upper face of the bench or table top while the lower arm —3— is disposed in a vertical plane substantially midway between the arms 70 —2— and is provided with a threaded opening —4— for receiving a vertically adjustable clamping screw —5— having a head —6— adapted to engage the underside of the bench or table top and together with the 75 arms —2— constituting means by which the frame may be clamped to or removed from the bench or table.

The frame —1— is preferably composed of sections —7— and —8— having relatively 80 large circular chambers —9— in their adjacent faces to form a gear housing, the sections —7— and —8— being secured together face to face by clamping bolts —10—.

The arms —2— and —3— are preferably 85 formed upon the section —7— to permit said section to remain upon the bench ready for use, while the section —8— may be removed by simply loosening the clamping bolts —10— and such other parts of the machine 90 as may interfere with said removal when adjusted for use.

A horizontal operating shaft —11— is journaled in suitable bearings —12— in the frame —1— and is provided on its outer end 95 with a hand crank —13— by which it may be rotated.

A relatively large gear —14— is secured to the shaft —12— within the chamber —9— and is adapted to mesh with a relatively 100 small pinion —15— on the intermediate portion of the horizontal shaft —16— which is journaled at suitable bearings —17— in the upper portion of the frame —1— parallel with the operating shaft —11— and is therefore adapted to be driven at a relatively 105 high rate of speed.

A cylindrical grinder —18— of carborundum, emery or any other suitable material is secured to one end of the shaft —16— by 110

2
and between a pair of opposed collars —19— and —20—, one of which as —19— is seated in an annular recess —21— in the outer end of the grinder, the collar —20— being engaged with the adjacent end face of the bearing —17— to hold the shaft —16— and grinder —18— against movement in one direction.

10 The other end of the shaft —16— is provided with a collar —22— tight thereon for engaging the adjacent end of the bearing —17— to hold the shaft —16— and grinder —18— against endwise movement in the opposite direction.

15 The object of the recess —21— in the outer end of the grinder —18— is to permit the clamping collar —19— to lie wholly within said end face so that certain classes 20 of work to be ground or polished may be moved across the entire area of said end face.

25 The pinion —15— is preferably formed in the shaft —16— as a unitary part thereof by simply cutting the teeth in its periphery to mesh with the gear —14—.

30 A bracket —23— is adjustably secured by bolts —23'— and slots —23''— to the outer end face of section —7— of the frame —1— and is provided with a split journal bearing —24— in which is journaled a rotary upright shaft —25— and is also provided in its lower end with a gear chamber —26— and a laterally offset bearing —27— for receiving respectively a worm gear —28— and 35 a rotary shaft —29—, said bracket and parts carried thereby being adjustable about the axis of the shaft —29— to permit the work, as —a— to be adjusted toward and from the axis of grinders of different diameters, 40 or as the periphery of the grinder —18— is worn away.

45 The worm gear —28— is secured to the lower reduced end of the upright shaft —25—, said reduced end being extended downwardly and journaled in a suitable opening in a bushing —29'— which is screwed into the lower end of the gear chamber —26— to form an end thrust bearing for the lower end of the hub of the gear —28— and thereby to hold said gear and shaft —25— against downward movement relatively to the bracket —23—.

50 The shaft —29— extends horizontally parallel with the grinder shaft —11— and 55 to opposite sides of the worm gear —28—, and also across the periphery of the relatively large gear —14— where it is provided with a relatively small pinion —20— meshing with said gear to receive rotary motion therefrom and whereby the shaft —29— will be driven at a relatively high rate of speed as compared with that of the shaft —11—.

55 The intermediate portion of the shaft —29— is provided with a gear worm —31—

meshing with the gear —28— for driving the upright shaft —25— at a considerably lower rate of speed than that of the shaft —29— having a purpose presently described.

70 A horizontal bearing —32— having an offset upright hub —33—, is supported upon the upper end of the bearing —24— of the bracket —23— and also upon the upper end of the shaft —25— so as to extend partially 75 across the face of the rotary grinder —18— and is adjustable angularly about the axis of the upright shaft —25— to different angles relatively to the axis of the grinder —18—.

80 This horizontal bearing —32— is adapted to receive and support a rotary work holder —35— which comprises a sleeve —36— and a collet chuck —37—, the latter being adapted to receive and support the work such, for 85 example, as the stem —a'— of a poppet valve —a—.

86 The sleeve —36— is journaled in the bearing —32— for relative rotation therein and is provided intermediate its ends with a worm gear —38— formed by cutting the teeth in the periphery of the sleeve and adapted to mesh with a gear worm —39— on the upper end of the upright shaft —25— Figure 5.

90 The chuck —37— preferably consists of tube split longitudinally through portions of its length from both ends and having each end tapered for engaging similarly tapered end thrust bearings —40— and —40'— at 100 corresponding ends of the chuck, the tapered bearing —40— being preferably formed on the adjacent end of the sleeve —36— while the other tapered bearing —40'— is movable axially within the sleeve and is adapted to be tightened and released for clamping and releasing the work by means of an adjusting screw —41— in the adjacent end of the sleeve.

105 The axially adjustable bearing —40'— and screw —41— are provided with registering openings coaxial with the axis of the tubular chuck —35— to permit the stem of the valve to extend thereinto when the head of the valve at the opposite end of the bearing —32— is in position for grinding.

110 When it is desired to clamp the stem of the valve in the chuck —35— the screw —41— will be turned to force the movable bearing —40'— toward the other bearing —40— thereby causing both ends of the split collet or chuck —35— to be compressed tightly upon the valve stem to more firmly hold the valve against vibration during the 115 grinding operation.

120 Reversing the direction of the rotation of the screw —41— will release the conical bearing —32— and thereby permit the jaws of the chuck —35— to open for releasing the valve stem and permitting the valve to 125 130

be withdrawn after it has been properly ground.

The head of the screw —41— is provided with an annular groove —42— for receiving the peripheral portion of the head —43— of a stop screw —44— which is adjustable in a threaded boss —45— on the under side of the bearing —32— and is frictionally held in its adjusted position by a friction screw —46— in one side of the lug —45—.

The object of engaging the head —43— of the stop screw —44— in the grooved head of the screw —41— is to prevent accidental turning of said screw during the rotation of the work holder with the work therein particularly when the latter is engaged with the rotary grinder —18—.

The work holder is arranged in such manner as to support the part of the work to be ground, as, for example, the valve head —a— in contact with the outer end face of the rotary grinder —18— in approximately the horizontal plane of the axis of said grinder so that when the grinder is rotated at a relatively high rate of speed the valve or other work held in the chuck —35— will be rotated at a relatively low rate of speed so as to produce a smooth finish on the work during one revolution of the work holder and at the same time reducing the liability of vibration of the work in the holder.

The angle of the seating faces of different valves varies and it therefore becomes necessary to adjust the bearing —32— and work holder therein to different angles relatively to the axis of the grinder or rather relatively to the outer end face of the grinder, the angles of the valves being known and in order that the operator may set the work holder at the desired angle the periphery of the base of the upright hub —33— of the bearing —32— is graduated circumferentially at —47— to register with a fixed mark —48— on the adjacent upper end of the hub —24— Figure 3.

Trueing device.

In order that the seating face of the valve may be ground to true form and angle, it is necessary to keep the outer end face of the rotary grinder in a truly flat plane at right angles to its axis of rotation and for this purpose is provided a suitable trueing device consisting of a peripherally toothed trueing wheel —48— which is journaled in the upper bifurcated end of an upright lever —49— which is pivoted intermediate its ends at —50— to the upper bifurcated end of a rock arm —51—, the latter having its lower end pivoted at —52— to a supporting arm —53— Figures 1 and 6.

This supporting arm —53— is provided with a split cap —54— which is seated over and upon the outer end of the bearing —27— to engage the corresponding outer end of the

shaft —29— so that when the cap —54— is firmly clamped to the bearing —27— it will hold the shaft —29— against outward endwise movement in case its direction of rotation should be reversed by reversing the direction of rotation of the grinding element from that required to produce the desired grinding effect upon the valve, it being understood that the contacting faces of the grinder and valve move in opposite directions during the grinding operation.

The other end of the shaft —29— opposite that which is engaged by the cap —54— is reduced to form a shoulder at the adjacent end of the pinion —30— for limiting the movement of the shaft in that direction during the regular grinding operation.

The lever —49— extends downwardly some distance beyond its pivot —50— and is provided with a threaded opening for receiving an adjusting screw —55— which is adapted to engage the rock arm —51— and thereby to force the trueing wheel —48— on the upper end of the lever into engagement with the adjacent face of the grinder for trueing purposes, said lever being provided with a handle —56— by which it, together with the rock arm —51—, may be moved about the axis of the pivot —52— for moving the trueing wheel —48— across the outer end face of the grinder.

The pivot —52— is parallel with the axis of the grinder so that adjusting the lever —49— by means of the screw —55— to cause the trueing wheel —48— to contact with any one portion of the grinder and then moving the lever laterally about the axis of the pivot —52— will cause the outer end face of the grinder to be trued to a flat plane at right angles to its axis of rotation for producing a smooth finish of the face of the valve when the latter is rotated thereagainst.

Drill holder.

Suitable means is provided for accurately grinding the points of drills, said means comprising in this instance a drill holder —58— Figures 1, 2 and 7, supported in an inclined plane at an angle to the outer end face of the grinder corresponding to the angle to which the point of the drill is to be ground, the upper face of the support —58— being provided with a V-shaped groove —59— in which the drill is adapted to lie lengthwise with its point facing the grinder in such manner as to grind the portion of said point to the desired angle below the axis of the drill.

For this purpose the support —58— is provided near its end adjacent the grinder with a downwardly projecting pivotal stud —60— at substantially right angles to the base of the groove —59— and journaled in a suitable bearing —61— which forms a part of a supporting bracket —62— on the

frame —1— and is inclined upwardly at an angle to and away from the adjacent end face of the grinder —18— to support the drill at the desired angle relatively to the grinding face and at the same time to permit the support to be rocked by hand laterally about the axis of the pivotal stud —60— for imparting a circumferentially convex curvature to the portion of the drill point being ground.

10 During the grinding operation of the point of the drill the latter may be rotated by hand in the groove —59— to present different portions of the drill point to the grinder with the assurance that all parts will be ground at a uniform angle and circumferential curvature.

In order to assure this uniform grinding of the point of the drill the opposite end of 20 the drill is engaged by an adjusting screw —63— which is engaged in a threaded aperture —58'— in the outer upwardly offset end of the support —58— and is provided with a handle —63'— by which it may be rotated for axial adjustment according to the length of the drill.

The bracket —62— extends across the periphery of the grinder —18— opposite the work holder —35— and is provided at its 30 inner end with a downwardly projecting arm —62'— having a lengthwise slot —64— for receiving a clamping bolt —65— which passes through a slot —66— in an arm —67— on the frame section —8—, said arm —67— being therefore stationary relatively to the frame while the bracket —62— may be adjusted vertically and horizontally and to different angles about the axis of the clamping bolt —65— and held in any 40 of its adjusted positions by the tightening of said bolt.

The portion of the bracket —62— which extends across the periphery of the grinder —18— constitutes a work rest having a 45 beveled upper face and may be adjusted to different angles relatively to the adjacent grinding face as may be required for grinding different kinds of work by simply adjusting the arm —62'— vertically and horizontally as permitted by the slots —64— and —66— and then tightening the bracket in place by the clamping bolt —65—.

Shear holder.

55 The bracket —62— is provided at its inner side with an upright extension —70— adjacent one of the end faces of the grinder —18— preferably opposite the drill holder —58—, said extension being provided with a 60 beveled upper face —71— disposed at an angle to the adjacent end face of the grinder corresponding to the angle at which the cutting edge of a shear blade is to be ground.

That is, the upper beveled face of the extension —70— forms a rest upon which the

blade of the shears may be supported with its cutting edge extending across and against the adjacent end face of the grinder for grinding the cutting edge of the shear blade to the desired bevel or angle.

When grinding a shear blade, the bracket —62— will be adjusted to bring the beveled face —71— in a plane some distance above the axis of the grinder but below the top of the grinder thus permitting the use of the major portion of the adjacent end face of the grinder above the collar —20— for grinding the whole or the greater part of the length of a shear blade in one operation.

Chisel holder.

The upright extension —70— of the bracket —62— is also provided with a transverse guide opening or slot —72— for receiving the blade of a chisel —C—, said guide opening or slot —72— being disposed at an angle to the adjacent end face of the grinder —18— corresponding to the angle at which the cutting edge of the chisel is to be ground.

When it is desired to grind the cutting edge of the chisel, the cutting end of the blade is inserted through the slot —72— to bring its cutting edge against the adjacent end face of the grinder where it is held by hand until brought to the desired finish.

It will be evident from the foregoing descriptions that these various work holders are arranged in definite relation to the grinder or to the axis of rotation thereof and are also arranged in definite relation to each other so that either may be used for its particular work without interfering with the other holders, thus making it possible for several operators to use the same stone at the same time. For example, one operator might be grinding valves, another operator grinding a drill point and still another operator may be grinding various knives or chisels and at the same time one of the operators, as for example the one grinding the valves, may manipulate the trueing device for keeping the outer end face of the grinder in a flat plane, it being understood that the arm —53—, Figures 1 and 6, may be adjusted about the axis of the shaft —29— and also about the axis of the pivotal bolt —52— so that the trueing wheel —48— may be caused to sweep across the face of the grinder without interfering with any of the other operations.

Operation.

The crank arm —13— is adapted to be rotated by hand clockwise at any suitable speed for rotating the grinder in a reverse direction at a considerably higher rate of speed through the medium of the relatively large gear —14— and pinion —15—.

This rotation of the gear —14— will im-

part a rotary motion to the shaft —29—, Figure 4, through the medium of the pinion —30— meshing therewith, which rotary motion will be again transmitted to the upright shaft —25— Figure 5, through the medium of the worm —31— and gear —28— and thence through the worm —39— and gear —38— to the work holder —35 in which the work, such for example as the valve —a—, is held and rotated against the outer end face of the grindstone.

The angle of contact of the work in the holder —35— relatively to the grinding face of the grinder —18— may be changed at 15 will by simply adjusting the bearing —32— about the axis of the shaft —25—.

The trueing device may be operated by hand through the medium of the handle —56— across the adjacent end face of the 20 grinder whenever it is necessary to true said face but may be withdrawn from contact with the grinder by simply loosening the adjusting screw —55—.

In grinding the cutting point of the drill 25 the latter is simply laid lengthwise in the groove —59— of the support —58— with the point facing the adjacent end of the grinder after which it may be adjusted to contact with the grinder by means of the 30 screw —63— engaging the end of the shank of the drill, said drill being rotated by hand to cause all portions of its point to be ground to the same bevel or angle.

Various articles not necessary to herein 35 illustrate or describe may be supported upon the beveled upper face of the bracket —62— to contact with the periphery of the grinder for grinding purposes.

In grinding shears, the blade is held flat- 40 wise against the beveled face —71— with its cutting edge against the adjacent end face of the grinder and is then moved end- wise as may be required to impart the de- sired finish to the cutting of the blade.

In grinding a chisel the blade of the lat- 45 ter is inserted through the slot —72— with its cutting edge against the inner face of the grinder to impart the necessary finish thereto.

50 What I claim is:—

1. In a grinding machine of the character described, a gear case, a horizontal driving shaft journaled in the gear case, means for rotating said shaft, separate driven shafts 55 journaled in the gear case parallel with the driving shaft, gearing within said case for transmitting rotary motion from the driving shaft to both of the driven shafts, a grinding wheel secured to one of the driven shafts, a bracket mounted on the gear case, an upright shaft journaled on said bracket,

means for transmitting rotary motion from the other driven shaft to the upright shaft, a horizontal bearing member mounted on the bracket for angular adjustment about 65 the axis of the upright shaft, a rotary work-holder journaled on said bearing member at one side of the axis of the upright shaft, and means for transmitting rotary motion from the upright shaft to the work-holder. 70

2. In a grinding machine of the character described, a rotary driving shaft, means for rotating said shaft, a relatively large gear secured to the driving shaft, separate rotary driven shafts parallel with the driving shaft 75 and provided with pinions meshing with said gear, a grinding wheel secured to one of said driven shafts, a rotary work-holder, and means for transmitting rotary motion from the other driven shaft to said work- 80 holder.

3. In a grinding machine of the character described, a gear case, a driving shaft journaled on the gear case, means for rotating said shaft, separate driven shafts journaled 85 on the gear case, means for transmitting rotary motion from the driving shaft to both of the driven shafts, a grinding wheel secured to one of the driven shafts, a bracket mounted on the gear case, an additional shaft 90 journaled on the bracket, means for transmitting rotary motion from the other driven shaft to said additional shaft, a bearing member mounted on the bracket, a rotary work-holder journaled in the bearing mem- 95 ber, and means for transmitting rotary motion from said additional shaft to the work- holder.

4. In a grinding machine of the character described, a gear case, a driving shaft journaled on the gear case, means for rotating said shaft, separate driven shafts journaled on the gear case, means for transmitting rotary motion from the driving shaft to both of the driven shafts, a grinding wheel se- 100 cured to one of the driven shafts, a bracket mounted on the gear case, an additional shaft journaled on the bracket, means for transmitting rotary motion from the other driven shaft to said additional shaft, a bear- 105 ing member mounted on the bracket, a ro- tary work-holder journaled in the bearing member, and means for transmitting rotary motion from said additional shaft to the work-holder, said bracket and parts carried thereby being adjustable about the axis of the second-named driven shaft to accommo- 110 date the work-holder to grinding wheels of different diameters. 115

In witness whereof I have hereunto set my 120 hand this 17th day of January, 1925.

JAMES HENRY LITTLER.
